UNITED STATES PATENT OFFICE.

JAMES McBLAIN, OF LONDON, ENGLAND.

ELECTRICAL APPARATUS FOR GENERATING OZONE.

Application filed April 12, 1924, Serial No. 706,048, and in Great Britain April 24, 1923.

This invention relates to improvements in electrical apparatus for generating ozone and the object of the invention is to so construct such an apparatus that a greater efficiency of output can be obtained from any given dimensions and/or weight of material than by the methods at present in use and incidentally to simplify and strengthen the construction of such apparatus.

10 According to my present invention the ozonator primarily consists in the construction of any suitable electrodes in a convolute form and in which either air or insulating material with distance or separating pieces 15 or other suitable means for securing the necessary air gap or aperture may be employed as the dielectric.

The electrodes may be of any width and may be of any number of convolutions.

20 The following description may be given as an example of construction in which an insulating material is employed as the dielectric. On one side of each of two bands or strips of a flexible ozone resisting insulating 25 material are secured, formed or deposited a flexible electrode of electrically conducting material the length and width of which are determined by the capacity required and by the purpose for which the ozonator is to be 30 used.

The length and width of the insulating bands or strips is considerably greater than those of the electrodes so as to provide an insulating margin around the four edges of 35 the electrodes mounted on them.

In order to provide a suitable gap or aperture between the electrodes for the passage of the atmospheric or other oxygen to be ozonized several methods may be adopted 40 such as the formation of ridges on one or both sides of the dielectrics by corrugating the latter, or by forming ridges on the surface of the material during its manufacture or such ridges may be provided by separate 45 pieces of suitable material secured in position. The aforesaid ridges in all cases are disposed transversely to the length of the band or strip.

Or alternatively, a suitable passage for the atmospheric or other oxygen to be ozonized 50 may be provided by so forming one or both of the flexible electrodes that such atmospheric or other oxygen may pass through it or them and along and about the points or parts of the electrode or electrodes which are in contact with the dielectrics.

In order that my invention may be clearly understood reference may now be had to the accompanying sheet of drawing in which—

Figure 1 is a perspective fragmentary view of one form of element that may be employed for the construction of an ozone generator and

Figures 2, 3 and 4 are diagrammatic views of alternative construction of similar elements whilst,

Figure 5 is a front elevation of a complete apparatus and

Figure 6 a side elevation of Figure 5 the upper half being in section.

Figure 7 is a plan and Figure 8 a section on line $x-x$ of Figure 7 showing the construction of a preferred form of electrode to an enlarged scale.

Similar letters of reference relate to like parts in all the figures of the drawing.

Referring to Figures 1 2 5 and 6 it will be seen that in one constructional form of an ozone generator according to this invention I take the two bands or strips of flexible ozone resisting insulating material $a-b$ on one side of each of which a flexible electrode c is secured and upon these bands distance pieces of insulating material d are transversely disposed and fastened thereto by any convenient means. One such band or strip is then placed on top of and parallel to the other with the similar surfaces facing upwards as shown in Figures 1 and 2 (in the latter the electrode being depicted by the dash line) and the two superimposed strips are rolled or convolved together and the whole secured in a suitable pipe ring or frame e as shown in Figures 5 and 6. In this form of construction the generation and discharge of ozone takes place in and from the space f between the electrodes c and the dielectrics $a-b$ and preferably the electrical component which energizes the electrodes c is contained in a suitable circular housing g that serves the purpose of a support for the several convolutions of the ozone generating elements aforesaid.

The housing g contains the usual primary and secondary coils h and i respectively and suitable terminal sockets j and k are provided for the connection to the source of current supply as shown in Figures 5 and 6.

Figure 3 shows another form of ozone generator element wherein the electrode c (shown in broken lines) and ridge pieces d are secured as previously described to the

two bands or strips *a*—*b* and then another band or strip of flexible ozone resisting insulating material *a'*—*b'* is fastened to the other side of the ridge piece *d* and the whole rolled or convolved and secured as above described.

In this form of construction the radiation or discharge which generates ozone is between two dielectrics that is to say the space 10 *f* between the two bands or strips of flexible ozone resisting insulating material *a*—*b'* which are supported by the ridge pieces and in such an ozone generator there is provided an annular gap or aperture for the 15 generation of ozone of a width equal to the thickness of the ridge pieces and excepting for the interruption of the latter of a length approximately equal to the length of the electrodes.

20 Figure 4 shows another modification of the construction of an ozone generator element wherein the electrode *c'* is of a corrugated form contained between the dielectrics that constitute the air gap *f*.

25 It will be obvious that the dielectric strips or bands may be corrugated or ridge pieces formed thereon instead of the electrode being corrugated as shown whereby the same effect is obtained with the use of a flat 30 strip electrode.

A preferred form of electrode suitable for embodying in any of the above described constructions is illustrated in Figures 7 and 35 8 and comprises a sheet or strip of electrical- 40 ly conducting material 2 the upper and lower surfaces of which are pressed into hollow cones or pyramids 3, 4 respectively in such a manner that the apices 5 of the hollow cones or pyramids 3, 4 are burst or pierced 45 whereby the active points are intensified and consequently increased efficiency obtained. The proportion or number of the hollow cones or pyramids provided on the surface of the sheet or strip 2 must not be less than 300 to the square inch.

In the forms of ozone generators in which a passage for the atmospheric or other oxygen to be ozonized is through the flexible electrode and along and about the points or 50 parts of the same which are in contact with the dielectric the methods of construction are similar to those already described except that in the case of such an electrode no corrugations or ridges need be used.

55 The methods of construction above described may be used separately or partly in combination and the number of electrodes may be more than two.

What I claim is:—

60 1. Electrical apparatus for generating

ozone comprising the combination with a plurality of metallic electrodes of a plurality of dielectrics comprising bands of insulating material upon which said electrodes are mounted, and means for providing the necessary air gaps between said electrodes and dielectrics that are wound upon one another in the form of a convolute. 65

2. Electrical apparatus for generating ozone comprising the combination with a 70 plurality of metallic electrodes of a plurality of dielectrics comprising bands of insulating material upon which said electrodes are mounted and a plurality of distance pieces of insulating material interposed between said electrodes and dielectrics that are wound upon one another in the form of a convolute. 75

3. Electrical apparatus for generating ozone comprising the combination with a 80 plurality of metallic corrugated electrodes of a plurality of dielectrics comprising bands of insulating material upon which said electrodes are mounted, said electrodes and dielectrics being wound upon one another in the form of a convolute. 85

4. Electrical apparatus for generating ozone comprising the combination with a 90 plurality of metallic electrodes of a plurality of dielectrics comprising corrugated 95 bands of insulating material upon which said electrodes are mounted, said electrodes and dielectrics being wound upon one another in the form of a convolute. 100

5. Electrical apparatus for generating ozone comprising the combination with a 105 plurality of electrodes comprising metallic electrically conducting bands the surfaces of which are pressed into hollow cones the apices of which are pierced of a plurality of dielectrics comprising bands of insulating material upon which said electrodes are mounted, and means for providing the necessary air gaps between said electrodes and dielectrics that are wound upon one another 110 in the form of a convolute. 115

6. Electrical apparatus for generating ozone comprising the combination with a plurality of metallic electrodes of a plurality of dielectrics comprising bands of insulating material upon which said electrodes are mounted, with means for providing the necessary air gaps between said electrodes and dielectrics that are wound in the form of a convolute upon the outside peripheral surface of a circular housing.

In testimony whereof I affix my signature.

JAMES McBLAIN.
